Aircraft Corporation, a corporation of Dela-
ware

Application April 3, 1941, Serial No. 386,665

8 Claims. (Cl. 89—33)

The present invention relates generally to ammunition magazines for machine guns. More particularly the invention relates to that type of ammunition magazine which is expressly or primarily designed for use in connection with a machine gun in the wing of an airplane, is disposed in, and extends longitudinally of, the wing, and serves to support a flexible cartridge belt in a serpentine or sinuous manner so that it is in readiness for automatic feed through the breech opening of the machine gun by means of the usual machine gun feed means.

One object of the invention is to provide an ammunition magazine of this type which is an improvement upon, and has certain inherent advantages over, previously designed magazines of the same general type or character and for the same purpose and is characterized by the fact that it is so designed and constructed that the cartridge belt moves or feeds freely from it with a minimum amount of frictional retardation.

Another object of the invention is to provide an ammunition magazine of the aforementioned type which is in the form of an elongated housing and has a plurality of serially connected superposed channels whereby the various strands of the cartridge belt are supported independently of one another and the belt as a whole is properly held regardless of the flight attitude of the airplane and hence is not likely to jam in connection with feed thereof to the machine gun.

Another object of the invention is to provide a machine gun ammunition magazine of the last mentioned character in which the superposed channels are serially connected at the ends thereof by curved channel sections of substantially semi-circular shape and are so designed or shaped as far as cross section is concerned that it is impossible to feed the belt into them in connection with loading of the magazine unless the cartridges are properly positioned for firing by the machine gun with which the magazine is associated.

A further object of the invention is to provide an ammunition magazine of the type and character last mentioned in which one end of one of the superposed channels is disposed adjacent the breech opening of the machine gun and has a lock-equipped door associated therewith whereby the cartridge belt may be fed into the magazine in connection with charging or loading thereof.

A still further object of the invention is to provide a combined ammunition container and feed means which is generally of new and im-

proved construction and not only is efficient in operation but also is light in weight and does not interfere with the reenforcing structure of the airplane wing with which it is employed.

Other objects of the invention and the various advantages and characteristics of the improved magazine and its feed means will be apparent from a consideration of the following detailed description.

10 The invention consists in the several novel features which are hereinafter set forth and are more particularly defined by claims at the conclusion hereof.

In the drawings which accompany and form 15 a part of this specification or disclosure and in which like numerals of reference denote corresponding parts throughout the several views:

Figure 1 is a plan view of an airplane wing having mounted therein a machine gun together 20 with a combined ammunition magazine and automatic feed means embodying the invention, a portion of the skin of the wing being broken away for purposes of illustration;

Figure 2 is a fragmentary plan view showing 25 the construction and design of the magazine and illustrating the position or location of the star wheel for positively feeding the cartridge belt into the magazine during charging or loading of the latter and also forcing or urging the cartridge belt to the machine gun in connection with use of the latter;

Figure 3 is a front view of the magazine illustrating the manner in which the upper channel is connected to the breech opening of the machine 35 gun and showing the manner in which the cartridge belt is fed into the magazine during charging of the latter;

Figure 4 is a vertical transverse section taken on the line 4—4 of Figure 3 and showing in detail 40 the design and arrangement of the star wheel and the spirally grooved drum constituting part of the power means for reversely rotating the star wheel in connection with feed of the belt to the gun;

Figure 5 is a vertical longitudinal section of the container showing in detail the manner in which the channels serve to separate or space apart the various strands of the belt;

Figure 6 is a detailed front view of the outer 50 end of the magazine;

Figure 7 is a vertical transverse section taken on the line 7—7 of Figure 5 and showing in detail the cross sectional design of the superposed channels;

Figure 8 is an enlarged vertical longitudinal

section of the inner end of the magazine, taken on the line 8—8 of Figure 2;

Figure 9 is a vertical transverse section taken on the line 9—9 of Figure 5; and

Figure 10 is a perspective view of a part or portion of the cartridge belt.

The combined magazine and automatic feed means which is shown in the drawings constitutes the preferred form or embodiment of the invention. It is shown in connection with, and as forming a part of, the wing A of an airplane having a machine gun G and serves, as herein-after described, to retain and feed a cartridge belt B to the gun. The airplane wing A is of standard or conventional design and comprises a front longitudinally extending spar a, a rear longitudinally extending spar a¹ and a series of laterally spaced cross ribs a². Such parts of elements of the wing are surrounded by a skin a³ of sheet metal or other material. The inner ends of the front and rear spars together with certain of the innermost cross ribs define a compartment a⁴ for the machine gun G. Access to this compartment is provided by way of an opening a⁵ in the superincumbent or superjacent portion of the skin a³. A panel a⁶ serves as a removable closure for the opening a⁵. The machine gun G is mounted in a fixed position within the compartment a⁴ and extends transversely of the wing A. The barrel of the gun projects forwards and is aligned with a tube or apertured cap a⁷ in the leading edge of the wing. The gun G has in the breech thereof a transversely extending opening through which the cartridge belt B is adapted to be fed. In addition to the opening the gun G includes conventional or standard automatic feed means for the belt and when the gun is fired the belt feeds through the breech opening and the cartridges are successively fired in a forwards direction through the barrel of the gun and the tube or apertured cap a⁷ in the leading edge of the wing. The belt B when stored or in place in the magazine, is arranged in a serpentine or zigzag manner, as hereinafter described. It is of conventional design and comprises a series of clips which serve to hold, and are interlocked by, the cartridges. The intermediate cross ribs have aligned openings a⁸ in the central portions thereof, that is, the portions between the front and rear spars a and a¹.

The magazine serves as a retaining or storage medium for the cartridge belt B and comprises an elongated tube-like housing 11 and a pair of fittings 12 and 13 at the ends of the housing.

The housing is mounted in, and extends lengthwise of the wing A. It extends through, and fits snugly within, the openings a⁸ in the central portions of the intermediate cross ribs a² of the wing and comprises a front wall 14, a back wall 15, a top wall 16 and a bottom wall 17. These walls are formed of sheet metal or other suitable material and are rigidly secured together. The top and bottom walls have a plurality of holes 18 therein in order to reduce to a minimum the weight of the magazine as a whole. The interior of the elongated housing 11 is divided into a longitudinally extending upper channel 19, a longitudinally extending lower channel 20, and a longitudinally extending central or intermediate channel 21 by way of four vertically spaced longitudinally extending inwardly projecting ribs 22 on the front wall 14 and four vertically spaced longitudinally extending inwardly projecting ribs 23 on the back wall 15 of the housing (see Figure 7). The ribs 22 are formed

integrally with the front wall of the housing and by bending such wall back and forth, as indicated in Figure 7. The grooves which are formed between the ribs 22 constitute the front side portions of the longitudinally extending channels 19, 20 and 21 and are adapted to receive the projectile parts of the cartridges on the belt B. The ribs 23 on the back wall 15 of the housing are formed by bending such wall back and forth as clearly disclosed or illustrated in Figure 7 of the drawings. The grooves which are disposed between the ribs 23 define the back side portions of the channels and are adapted to receive the butt ends of the cartridges, that is, the ends with the percussion caps. The ribs 22 are of greater thickness than the ribs 23 with the result that the grooves between them are of less height than the grooves between said ribs 23 and hence it is impossible to insert the cartridge belt B into the channels 19, 20 and 21 unless the cartridges are properly arranged for firing by the machine gun G. In other words, the grooves between the ribs 22 will accommodate only the narrow projectile parts of the cartridges and it is thus impossible to load or charge the magazine unless the cartridges on the belt B are positioned with the projectile parts pointing or facing forwards. When the housing of the magazine is charged the belt is arranged in a zigzag manner within the superposed channels and the cartridges in each strand of the belt are out of contact with the cartridges of the other strands because of the spacing of the channels due to the inwardly projecting ribs on the front and back walls 14 and 15. A plurality of vertically extending laterally spaced channel bars 24 are welded or otherwise fixedly secured to the front wall 14 of the housing in order to reinforce the latter and prevent vertical expansion or contraction thereof. Similar channel bars 25 are welded or otherwise secured to the rear face of the back wall 15 of the housing.

The fitting 12 is located at the outer end of the housing 11 and is connected to such end of the housing by way of a hollow bracket 26 (see Figure 6). It comprises a front wall 27, a back wall 28 and a substantially continuous intermediate wall 29. The front and back walls are substantially circular as far as contour is concerned and embody inwardly extending extensions which are aligned with the outer ends of the front and back walls of the housing 11 and are suitably secured to the side portions of the hollow bracket 26. They are spaced apart by the intermediate wall 29 and have inwardly extending ribs which define a curved channel section 30 (see Figure 4). The latter is joined to, and serves serially to connect, the outer ends of the upper and lower channels 19 and 20 in the main magazine housing 11. When the cartridge belt B is inserted into the upper channel 19 and is then slid outwards in the direction of the fitting 12 in connection with loading of the magazine it travels or passes first through the channel 19, then around the curved channel section 30 in the fitting 12 and then inwards through the lower channel 20 in the housing 11. The front and back walls 27 and 28 of the fitting 12 are formed of sheet metal or any other suitable material. The intermediate wall 29 is curved in conformity with the peripheries or edges of the front and back walls 27 and 28 and is joined at its ends to the top and bottom portions of the hollow bracket 26. The thickness of the front portion of the channel section 30 corresponds to the

thickness of the front portion of any one of the longitudinally extending channel sections in the housing 11 and the rear portion of said channel section 30 corresponds in thickness to the back portion of any one of said channel sections in the housing.

The fitting 13 is located at the inner end of the housing 11, as best shown in Figures 3 and 5, and like the fitting 12, is formed of sheet metal. It comprises a front wall 31, a back wall 32, and a substantially continuous intermediate wall 33. The front and back walls of the fitting 13 are provided with inwardly projecting ribs and these define a curved channel section 34 which extends between, and serves serially to connect, the inner ends of the lower channel 20 and the intermediate channel 21 in the magazine housing 11. Said front and back walls 31 and 32 are aligned with the inner ends of the front and back walls of the housing 11 and are secured thereto by way of attaching plates 35. The latter are welded or otherwise fixedly secured to the front and back walls of the fitting 13 and have outwardly extending extensions which lap and are welded to the inner ends of the front and back walls of the housing 11. The intermediate wall 33 extends between, and serves to space apart, the front and back walls 31 and 32 and corresponds in shape to the marginal portions of said front and back walls. It assists in defining the curved channel section 34 and is formed of sheet metal or other suitable material. When the belt B is fed into the magazine in connection with charging of the latter it travels inwards through the lower channel 20 in the housing 11 after passing through the curved channel section 30 in the fitting 12, then travels around the curved channel section 34 in the fitting 13, and finally travels or moves into the intermediate channel section 21 in the housing 11. The outer end of the intermediate channel 21 is closed by way of a cross wall 36 (see Figure 5). The front portion of the curved channel section 34 corresponds in thickness to the front portion of the curved channel section 30 in the fitting 12 and the rear portion of said curved channel section 34 corresponds in thickness to the rear portion of the curved channel section in said fitting 12.

In addition to the housing 11 and the end fittings 12 and 13 the magazine comprises an open ended trunk 37. This trunk extends between, and serves to connect, the inner end of the upper channel 19 and the breech opening in the machine gun G. It is rectangular in cross section and has the outer end thereof connected by way of a hinge 38 to the inner end of the top wall 16 of the housing 11. The inner or discharge end of the trunk is supported in alignment with the breech opening in the machine gun by way of a vertically adjustable post 39. Such post is suitably supported on one of the structural elements of the airplane wing A, and permits, by reason of its adjustability, proper centering of the discharge end of the trunk with respect to the breech opening in the machine gun. The top wall of the trunk is provided with an opening 40 for magazine charging or loading purposes. A door 41 serves as a closure medium for this opening. One end of the door is connected by way of a hinge 42 to the top wall of the trunk and the other end embodies a latch type lock 43 whereby the door may be locked or secured in its closed position. The lock, as best shown in Figure 2, is in the form of a U-shaped wire which overlies the top of the

door. The crosspiece of the wire is connected to the hinged end of the door. The free ends of the side pieces of the wire project beyond the other end of the door and embody out-turned extensions 44 which are adapted to fit within a pair of oppositely positioned eyelets 45 on the inner extremity of the top wall of the trunk. When the extensions 44 are disposed within the eyelets the door 41 is locked in its closed position. To open the door it is only necessary to withdraw the extensions 44 from the eyelets. This is accomplished by squeezing the side pieces of the U-shaped wire toward one another a sufficient distance to effect complete withdrawal of the extensions from the eyelets. When the lock is in its unlocked position the door 41 may be swung upwards into its open position, as shown in full lines in Figure 3. The door 41 underlies the opening a⁵ in the upper portion of the skin of the airplane wing A and is accessible upon opening or removal of the panel a⁶.

For the purpose of charging the magazine with the belt B a chute 46 is provided. This chute is of U-shaped cross section and is adapted to guide the belt B into the magazine in connection with charging of the latter. In connection with charging of the magazine the panel a⁶ is first opened or removed. Thereafter the door 41 is unlocked and swung upwards into its open position in order to provide access to the opening 40 in the upper wall of the trunk 37. After upward swinging of the door 41 the lower end of the chute 46 is inserted through the opening 40 into the inner end of the trunk 37, as shown in Figure 3. After this step or operation one end of the belt B is slid down the chute 46 into the trunk 37. After insertion of one end of the belt into the trunk the belt is shifted or slid manually along the chute. During sliding of the belt the end first inserted into the trunk travels outwards along the upper channel 19, then around the curved channel section 30, then inwards along the lower channel 20, then upwards and outwards around the channel section 34 and finally outwards along or through the intermediate channel 21. As soon as the end of the belt that is in the intermediate channel strikes the cross wall 36 the operator can feed no more of the belt into the magazine and is duly apprised of the fact that the magazine is full or completely loaded. After loading of the magazine the chute 46 is removed from the trunk 37 and the adjacent end of the belt is fed through the breech opening in the machine gun G. Thereafter the door 41 is swung downwards into its closed position and is locked in place by manipulating the extensions 44 into the eyelets 45. After locking of the door the compartment a⁴ is closed by securing the panel a⁶ in its closed position.

In order to facilitate charging or loading of the magazine a star wheel 47 is provided. This star wheel is positioned within the fitting 12 at the outer end of the housing 11 and is rotatably mounted by way of a hollow shaft 48. The latter is disposed in parallel relation with the intermediate wall 29 of the fitting 12 and extends transversely of the housing 11. The front end of the shaft extends through, and is journaled in, a bearing 49 on the central portion of the front wall 27 of the fitting 12. The rear end of the shaft extends through, and is journaled in, a bearing 50 on the central portion of the back wall 28. The star wheel 47 is fixedly secured in any suitable manner to the portion of

the shaft that is within the fitting 12 and has cutouts on its periphery for receiving and accommodating the cartridges on the belt B (see Figures 4 and 5). The shaft 48 is so positioned that the star wheel is arranged in concentric relation with the curved channel section 30. When the star wheel, as viewed from the front, is turned in a clockwise direction in connection with charging of the magazine it forces the belt B in a positive manner around the curved channel section 30 through the lower channel 20 in the housing 11, thence around the curved channel section 34 and finally along the intermediate channel 21. Clockwise turning of the star wheel in connection with loading or charging of the magazine is effected by a removable or detachable crank 51. This crank comprises a shaft 52, a crank arm 53 and a handle 54. The crank arm 53 is connected to, and projects outwardly from, one end of the shaft 52. The other end of the shaft is provided with a diametric notch 55 for receiving and interlocking with a cross pin 56 within the central portion of the hollow shaft 48. In using the crank the notch equipped end of the shaft 52 is inserted into a hole 57 in the leading edge of the airplane wing A and is then shifted rearwards so that it passes through a bearing 58 and into the front end of the hollow shaft 48. The bearing 58, as shown in Figure 1, is mounted on, and extends through, the outer end of the front spar a^2 of the wing A. The hole 57 and the bearing are axially aligned with the shaft 47. When the shaft 52 of the crank is manipulated so that the cross pin 56 of the shaft 48 is in seated relation with the notch 55 a driving connection is established between the crank and the star wheel carrying shaft 48. When the crank is in driving relation with the shaft it may be turned in a clockwise manner so as to effect a positive feed of the belt B into the lower and intermediate channels of the housing in connection with loading or discharging of the magazine. In loading the magazine the crank 51 is first connected to the star wheel carrying shaft 48. Thereafter one end of the cartridge belt B is fed into the inner end of the upper channel 19 and is fed outwards along such channel until the extremity thereof comes in contact with the star wheel 47. When the leading end of the belt is in contact with the star wheel the operator turns the crank 51 in a clockwise direction. This results in a positive feed of the belt into the magazine. After complete loading of the magazine the crank is detached or removed from the wing A.

The feed means which is associated or combined with the magazine serves after charging or loading of the magazine reversely to rotate the star wheel in order to assist the feed means of the machine gun in feeding the belt through the breech opening in the gun. This means comprises an elastic cord 59 of the so-called "shock" variety, a wire cable 60 and a drum 61. The drum, as shown in Figures 1 and 4, is mounted on, and pinned to, the rear end of the hollow star wheel carrying shaft 48. It is disposed rearwards of the fitting 12 and has a cable receiving spiral groove 62 in its periphery. One end of the wire cable 60 is anchored to the drum in such manner that when the star wheel is rotated clockwise in connection with charging of the magazine the cable is wound around the drum. The other free end of the cable extends inwards alongside of the back wall 15 of the housing 11. The central portion of the elastic

shock cord 59 extends around a sheave 63. The latter is mounted on a bracket 64 on the central portion of one of the innermost cross ribs a^2 of the wing. One end of the cord extends outwards through holes in the central portions of the intermediate cross ribs and is anchored to a bracket 65. The other end of the shock cord extends outwards and is connected by a fitting 66 to the free end of the wire cable 60. The arrangement of the shock cord and cable is such that when the star wheel 47 is rotated in a clockwise manner in connection with charging of the magazine the shock cord is stretched and hence is placed under tension. When the star wheel is released from the crank 51 after loading or charging of the magazine the shock cord is so loaded that it tends reversely to rotate the star wheel. When the magazine is loaded the shock cord is under tension and hence when the machine gun is operated it operates through the medium of the wire cable 60 and the spirally grooved drum 61 to rotate the star wheel reversely and thus assist the feed means of the gun in feeding the cartridge belt through the breech opening in the gun. The shock cord 59 constitutes simple or improved means for supplementing or augmenting feeding of the cartridge belt through the machine gun G. If desired the shock cord may be partially elongated or stretched prior to loading of the magazine. This is accomplished by cranking the star wheel in a clockwise manner by the crank before the leading end of the belt reaches the star wheel in connection with charging of the magazine. The shock cord is effective or operative when a portion of the belt is in the curved channel section 30. When the belt is used to such an extent that no portion thereof is in said channel section 30 the supplemental feed means comprising the shock cord 59, the cable 60 and the drum 61 is ineffective or inoperative. When this occurs the portion of the belt in the upper channel 19 is capable of being readily fed through the machine gun by the machine gun feed means since it is in the form of a straight or rectilinear reach and is free from any reverse bends which would tend to place a strain upon the machine gun feed means. The elastic cord 59, the wire cable 60, and the drum 61 constitute or exemplify power means for rotating or driving the star wheel 47 in such direction as to feed the belt to the machine gun.

With a view of facilitating travel of the cartridge belt B around the curved channel section 34 in the fitting 12 at the inner end of the housing 11 a pair of rotary star wheels 67 is provided. These wheels are mounted in laterally spaced relation on a horizontally extending shaft 68 in said fitting 13. The ends of the shaft are journaled in bearings 69 on the inner faces of the attaching plates 35. The bearings are so arranged that the shaft and star wheels 67 are concentrically positioned with respect to the channel section 34. The wheels are adapted to engage the cartridges on the belt B, as shown in Figure 9, and tend to eliminate or materially reduce frictional retardation of the belt as it travels through or around the channel section 34 as well as maintain proper alignment of the belt as a whole.

In charging the magazine with the cartridge belt B the chute 46 is introduced into the inner end of the trunk 37, as hereinbefore described. Thereafter one end of the belt is slid down the chute into the trunk 37. After introducing one

end of the belt into the trunk the belt is slid outwards until the outer extremity thereof is in contact with the star wheel 47. At this point the operator, after connecting the crank 51 to the star wheel carrying shaft 48, turns the crank in a clockwise manner in order to feed the belt into the various channels of the magazine. During clockwise rotation of the star wheel the wire cable 60 is wound around the drum 61 and causes stretching of the shock cord 59, as hereinbefore set forth. As soon as the magazine is fully or completely charged the end of the belt B that is within the trunk 37 is introduced into the breach opening in the machine gun. Thereafter the crank 51 is removed and the door 41 and the panel a⁶ are locked in place. When the magazine is charged and the machine gun is operated the belt is fed through the machine gun by not only the feed means of the gun but also the supplemental or auxiliary feed means comprising the shock cord 59, the cable 60 and the drum 61.

The herein described combined magazine and feed means effectively and efficiently fulfills its intended purpose and is characterized by the fact that it eliminates any jamming of the cartridges. In addition it comprehends a free or ready feed of the cartridge belt to the machine gun with which it is associated and is especially practical in connection with cartridges of large caliber. The magazine as well as the feed means is light in weight and does not, to any material extent, interfere with the reinforcing structure of the airplane wing A. It may be readily installed and is capable of being quickly and easily loaded.

The invention is not to be understood as restricted to the details set forth since these may be modified within the scope of the appended claims without departing from the spirit and scope of the invention.

Having thus described the invention what I claim as new and desire to secure by Letters Patent is:

1. An ammunition magazine for a machine gun, comprising an elongated unitary housing structure having therein a serpentine channel for supporting a cartridge belt for lengthwise feed without the different strands thereof contacting one another, and composed of a main tubular housing embodying a pair of opposed spaced apart sheet metal walls bent back and forth to form a plurality of straight inwardly and longitudinally extending laterally spaced flat ribs arranged to form between and at right angles to the two walls three straight parallel spaced apart longitudinally extending channel sections, a separately formed fitting connected to one end of the housing and embodying a pair of opposed spaced apart sheet metal walls with instruck arcuate ribs arranged to form between and at right angles to the last mentioned walls a curved channel section connecting the adjacent end of one of the outer straight channel sections to the adjacent end of one of the other two straight channel sections, and a second separately formed fitting connected to the other end of the housing and embodying a pair of laterally spaced sheet metal walls with instruck arcuate ribs arranged to form between and at right angles to the last mentioned walls a curved channel section connecting the adjacent ends of said other two straight channel sections, the ribs on the walls of the housing and fittings that are at one side of the housing structure being spaced apart a certain distance and designed slidably to receive the projectile parts of the cartridges and the ribs

on the walls of said housing and fittings that are at the other side of the housing structure being spaced apart a greater distance and designed slidably to receive the butt ends of the cartridges.

2. An ammunition magazine for a machine gun, comprising an elongated unitary housing structure having therein a serpentine channel adapted to support a cartridge belt for lengthwise feed without the different strands thereof contacting one another, and composed of a main tubular housing embodying a pair of opposed spaced apart walls with straight inwardly and longitudinally extending laterally spaced flat ribs arranged to form between and at right angles to the two walls three straight parallel spaced apart longitudinally extending channel sections, a first separately formed hollow fitting connected to one end of the housing and embodying a pair of opposed spaced apart walls with inwardly extending arcuate ribs arranged to form between and at right angles to the last mentioned walls a curved channel section connecting the adjacent end of one of the outer straight channel sections to the adjacent end of the other outer straight channel section, and a second separately formed hollow fitting connected to the other end of the housing and embodying a pair of laterally spaced walls with inwardly extending arcuate ribs arranged to form between and at right angles to the last mentioned walls a curved channel section connecting the adjacent end of said other straight outer channel section to the adjacent end of the intermediate straight channel section, the ribs on the walls of the housing and fittings that are at one side of the housing structure being spaced apart a certain distance and designed slidably to receive the projectile parts of the cartridges and the ribs on the walls of said housing and fittings that are at the other side of the housing structure being spaced apart a greater distance and designed slidably to receive the butt ends of the cartridges.

3. An ammunition magazine for a machine gun, comprising an elongated unitary housing structure having therein a serpentine channel adapted to support a cartridge belt for lengthwise feed without the different strands thereof contacting one another, and composed of a main tubular housing embodying a pair of opposed spaced apart walls with straight inwardly and longitudinally extending laterally spaced flat ribs arranged to form between and at right angles to the two walls three straight parallel spaced apart longitudinally extending channel sections, a separately formed fitting connected to one end of the housing and embodying a pair of opposed spaced apart walls with inwardly extending arcuate ribs arranged to form between and at right angles to the last mentioned walls a curved channel section connecting the adjacent end of one of the outer straight channel sections to the adjacent end of one of the other two straight sections, and a second separately formed fitting connected to the other end of the housing and embodying a pair of laterally spaced walls with inwardly extending arcuate ribs arranged to form between and at right angles to the last mentioned walls a curved channel section connecting the adjacent ends of said other two straight sections, and rotary elements carried by the fittings between said walls thereof and in concentric relation with the curved channel sections and arranged to facilitate travel of the cartridge belt along the latter.

4. In combination with an airplane having a

machine gun mounted thereon, an ammunition magazine for the gun comprising a housing structure for a cartridge belt, mounted fixedly on the airplane in associated relation with the gun and having a discharge opening for the belt, facing in the direction of the cartridge opening of the machine gun, an elongated rigid hollow belt guiding member having one end thereof leading to, and terminating adjacent said cartridge opening of the machine gun and its other end communicating with the discharge opening of the housing structure and hinged to said structure so that the member as a whole may be swung bodily in order to center the one end with respect to said cartridge opening, and a longitudinally adjustable post extending between the airplane and said one end of the member and serving adjustably to support the member.

5. In combination with an airplane wing having a transversely extending machine gun mounted therein, an ammunition magazine for the gun, comprising an elongated housing structure for a cartridge belt, mounted fixedly in, and extending longitudinally of, the wing and having one end thereof disposed adjacent the machine gun and provided with a discharge opening, an elongated rigid trunk type member adapted to guide the belt from the discharge opening in the housing structure to the gun and having one end thereof movably connected to said one end of the housing structure so that the member as a whole may be moved bodily in order properly to align the other end thereof with the gun, and a support within the wing applied to said other end of the member and serving adjustably to support said member.

6. In combination with an airplane wing having a transversely extending machine gun mounted therein, an ammunition magazine for the gun, comprising an elongated housing structure for a cartridge belt, mounted fixedly in, and extending longitudinally of, the wing and having one end thereof disposed adjacent the machine gun and provided with a discharge opening, an elongated rigid trunk type member adapted to guide the belt from said opening to the gun, provided in the upper wall thereof with a door-closed opening whereby the belt prior to use thereof may be inserted through the member and into the housing structure in order to charge or load the latter, and having one end thereof leading to, and terminating adjacent, the cartridge opening of the machine gun and its other end communicating with said discharge opening of the housing structure and movably connected to said structure so that the member as a whole may be bodily adjusted in order to bring the one end thereof into centered relation with said cartridge opening in the gun, and an adjustable support disposed in the wing and applied to said one end of the member.

7. An ammunition magazine for a machine gun,

comprising an elongated unitary housing structure having therein a serpentine channel adapted to support a cartridge belt for lengthwise feed without the different strands contacting one another, and composed of a main tubular housing embodying a pair of opposed spaced apart walls with a plurality of straight inwardly and longitudinally extending laterally spaced flat ribs arranged to form between and at right angles to the two walls two straight parallel spaced apart longitudinally extending channel sections, and a separately formed fitting connected to one end of the housing and embodying a pair of opposed spaced apart walls with inwardly extending arcuate ribs arranged to form between and at right angles to the last mentioned walls a curved channel section connecting the adjacent end of one of the straight channel sections to the adjacent end of the other channel section, the ribs of the walls of the housing and fitting that are at one side of the housing structure being spaced apart a certain distance and designed slidably to receive the projectile parts of the cartridges and the ribs on the walls of said housing and fitting that are at the other side of the housing structure being spaced apart a greater distance and designed slidably to receive the butt ends of the cartridges.

8. An ammunition magazine for a machine gun, comprising an elongated unitary housing structure having therein a serpentine channel adapted to support a cartridge belt for lengthwise feed without the different strands contacting one another, and composed of a main tubular housing embodying a pair of opposed spaced apart walls with a plurality of straight inwardly and longitudinally extending laterally spaced flat ribs arranged to form between and at right angles to the two walls two straight parallel spaced apart longitudinally extending channel sections, and a separately formed fitting connected to one end of the housing and embodying a pair of opposed spaced apart walls with inwardly extending arcuate ribs arranged to form between and at right angles to the last mentioned walls a curved channel section connecting the adjacent end of one of the straight channel sections to the adjacent end of the other channel section, the ribs of the walls of the housing and fitting that are at one side of the housing structure being spaced apart a certain distance and designed slidably to receive the projectile parts of the cartridges and the ribs on the walls of said housing and fitting that are at the other side of the housing structure being spaced apart a greater distance and designed slidably to receive the butt ends of the cartridges, and a rotary element carried by the fitting between said walls thereof and in concentric relation with the curved channel section and arranged to facilitate travel of the cartridge belt along the latter.

GEORGE W. O'HARE.
